MACHINE FOR TIGHTENING CAPS ON CONTAINERS

Filed Jan. 11, 1945

UNITED STATES PATENT OFFICE

2,445,270

MACHINE FOR TIGHTENING CAPS
ON CONTAINERSJohn Hohl, Toledo, Ohio, assignor to Owens-
Illinois Glass Company, a corporation of Ohio

Application January 11, 1945, Serial No. 572,351

7 Claims. (Cl. 226—88)

1

My invention relates to machines for tightening caps or closure devices on containers such as jars, bottles and the like and is herein disclosed as embodied in a vacuum sealing machine in which jars are vacuumized and the closure caps then forced into position to seal the jars.

An object of the invention is to provide an improved construction adapted for sealing jars and the like with caps of the side or top seal type in which the cap is tightened or forced into position to seal the container by a straight downward pressure applied to the cap.

The invention as herein illustrated, is embodied in a machine of the type disclosed in the patent to Hohl et al., No. 2,338,852, Vacuum sealing machine, January 11, 1944. This patent discloses a machine for sealing jars and comprises means for rotating a screw cap to sealing position on the jar. The present invention comprises a novel mechanism by which top pressure is applied to the cap for forcing it into sealing position by a straight downward movement of the cap.

Referring to the accompanying drawings:

Fig. 1 is a fragmentary sectional elevation of the machine, showing particularly one of the vacuum sealing and cap tightening heads or units.

Fig. 2 is a fragmentary part-sectional plan view showing portions of adjoining units.

Fig. 3 is a fragmentary sectional elevation of a portion of the sealing unit shown in Fig. 1 but with the cap tightening pusher in its lifted position.

The mechanism herein shown comprises many features of construction the same as disclosed in said patent to Hohl et al. to which reference may be had for a full disclosure of the general construction and operation of the machine. Such machine includes a carriage or turret rotatable about a vertical axis and having thereon a plurality of vacuumizing and sealing units arranged in an annular series.

Referring to the drawings, the vacuumizing and sealing units 10 are mounted on a rotary platform 11 forming part of the carriage which is rotated about a vertical axis. Directly beneath each sealing unit is a pedestal comprising a platform 12 on which a container 13 is supported while being vacuumized and sealed. The platform is attached to a stem 14 which is mounted for up and down movement in bearings in a platform 14a forming part of the carriage, for moving the jar into and out of sealing engagement with the vacuum head or bell 15 which forms a part of the sealing unit. The bell 15

2

is attached to the under surface of the platform 11 and provides a vacuum chamber 16. The bell is formed with a tubular hub extension 17 which projects upward through an opening in the platform and is secured in place by a ring 18 threaded thereon. Bolts 19 provide additional attaching means and prevent rotation of the bell. A clamping ring 21 threaded on the lower end of the bell 15 serves to clamp a bearing ring 22 against a sealing gasket 23. A ring gasket 24 is clamped in position against the ring 22 by a clamping ring 25. When a jar 13 is moved upward into engagement with the gasket 24, it makes sealing contact therewith.

15 Each jar 13 has a closure device or cap C placed loosely thereon before the jar is lifted up to the sealing unit. The cap may be provided with a side sealing ring or top sealing gasket, the jar and cap being adapted to permit the cap 20 to be sealed on the jar by a straight downward pressure on the cap. When the jar is lifted into sealing contact with the gasket 24, suction may be applied in the chamber 16 for vacuumizing the jar. The cap is then forced downward to 25 sealing position by means of cap tightening mechanism including a pusher comprising a plate 26 which is moved up and down by means of a rotary tightening spindle 27, the operation of which will presently be described. The pusher plate 26 30 is held against rotation by a pin 28 attached to the vacuum bell. The pusher is provided with a face plate 29 attached to the plate 26 by screws 31. The face plate is preferably made of magnetic material and is magnetized to hold the 35 cap C as hereinafter described. A disk 32 of rubber or other resilient material, is interposed between the plate 26 and face plate 29 to permit an even distribution of pressure on the cap.

The tightening spindle 27 is tubular and is 40 journaled for rotation about its axis within the frame 33 of the sealing unit. An adapter 34, formed with an internal screw thread, is mounted on the lower end of the spindle 27 for rotation therewith. A key 35 secures the adapter against 45 rotation relatively to the spindle. The adapter is held up to the spindle by means of a ball 36 and lock screw 37. A spring-loaded packing gland 38 provides a seal between the spindle and its bearing. A screw shaft 40 formed with a left- 50 hand screw thread, is welded to the plate 26 and is threaded through the adapter 34. Rotation of the spindle 27 and attached adapter 34 operates through the nonrotatable screw shaft 40 to cause vertical movement of the pusher plate 26. 55 Mechanism for rotating the spindle 27 in-

cludes a coil spring 41 housed within the frame 33. The inner end of the spring is attached by a pin 42 to a sleeve 43 keyed to the spindle 27. The outer end of the spring is attached to a ring gear 44 mounted within the frame 33 and rotatably adjustable therein for adjusting the tension of the spring. This means for rotating the ring gear includes a shaft 45 mounted in the frame 33 and formed with gear teeth which mesh with those of the ring gear. This adjusting mechanism may be operated as fully set forth in the above mentioned patent.

The rotation of the spindle 27 is under the control of a stationary cam track 46 formed on the periphery of a stationary cam plate 47. Rock arms 48, individual to the sealing units are mounted for rotation, each about the axis of spindle 27, each arm being formed with a hub 49 surrounding the spindle and provided with roller bearings 50. Each arm 48 carries a cam follower roll 51 running on the cam track 46. The outer end of the arm 48 is formed with a segmental rack 52 which runs in mesh with gear teeth 53 formed on the sleeve 43. Each arm 48 is journaled in one sealing unit and operates the tightening device for the next sealing unit. The track 46 is concentric with the carriage for the greater portion of its circumference and includes a comparatively short re-entrant section controlling the rocking movements of the arms 48, said re-entrant portion comprising a section 54 controlling the inward swinging movement of the arm 48 and a section 55 which causes the outward movement of the arm. These operating sections 54 and 55 may be formed on a cam patch 56 removably mounted on the plate 47 and replaceable by other patches of different contours.

The operation is as follows:

While the spindle 27 is in its lifted position (Fig. 3) the jar 13 with a cap C loosely seated thereon, is lifted by the platform 12 into sealing contact with the gasket 24. Suction is then applied through the vacuum chamber 16 to vacuumize the jar and its contents. When the jar moves up to the sealing head, the cap is picked up and held by the magnetized face plate 29 as shown in Fig. 3. The space between the face plate 29 and the top surface 58 of the jar is somewhat narrower than the depth of the cap, so that if drawing of vacuum in the jar causes the cap to jump, it is prevented from slipping off the jar or becoming displaced. Immediately following the lifting and vacuumizing of the jar, the cam follower roll 51 runs onto the operating section 54 of the cam which permits the arm 48 to be swung inwardly by the coil spring 41, thereby rotating the cap tightening spindle 27 in a clockwise direction. The screw-threaded adapter or nut 34 being attached to the spindle and rotated thereby, forces the nonrotating screw shaft 46 and plate 26 downward, thereby forcing the cap C downward to sealing position on the jar 13. The cap is arrested in this position while the cam follower roll 51 is at an intermediate point on the operating cam section 54, so that the roll disengages the cam and the pressure applied to the cap is determined by the tension of the spring. After the cap has been thus forced onto the container, the cam section 55 swings the arm 48 outwardly, thereby rewinding the coil spring preparatory to the next operation. The vacuum in the bell 15 is released and the platform 12 moved downward with the sealed jar thereon. The parts are preferably so proportioned that less

than a complete rotation of the spindle is required to carry the pusher plate 26 through its full range of movement.

Modifications may be resorted to within the spirit and scope of my invention.

I claim:

1. A machine for tightening caps on containers, comprising a support for a container, a pusher plate, means for holding said pusher plate spaced above said support with the plate positioned over a container on the support and a cap loosely seated on the container, a vertical cap tightening spindle mounted over said plate, means for rotating the spindle about its axis, and means providing driving connections between the spindle and pusher plate including a screw shaft fixed to said plate and an internally screw-threaded element attached to said spindle for rotation therewith and in threaded engagement with said screw shaft, whereby rotation of the spindle causes vertical movement of said pusher plate, said means for rotating the spindle comprising a coil spring surrounding and connected to the spindle for rotating it in one direction, and positive means for rotating the spindle in the opposite direction.

2. A machine for vacuumizing and sealing jars or other containers, said machine comprising a platform forming a support for a container with a cap loosely placed on the container, a downwardly opening vacuum chamber spaced above said platform, means for holding the platform with the container thereon in position for the container to seal said chamber, a pusher plate within said chamber, a vertical screw shaft attached to said plate, a vertical spindle above and in alignment with said screw shaft, an adapter connected to the spindle for rotation therewith and having a screw-threaded connection with said screw shaft, means for holding the pusher plate against rotation, means for rotating said spindle back and forth about its axis for moving the pusher plate downward and forcing the cap into sealing position on the jar and for withdrawing the pusher plate, means for rotating said spindle comprising a coil spring connected to and applying a driving torque to the spindle, an arm having a driving connection with the spindle, and a cam controlling the movement of said arm, thereby controlling the rotation of the spindle by the spring in one direction, said cam including a section arranged to rotate the spindle in the opposite direction.

3. A machine for tightening caps on jars comprising a support for a jar with a cap loosely seated thereon, a vertical cap tightening spindle spaced above said support, a pusher plate beneath said spindle, a screw shaft fixed to said plate in vertical alignment with the spindle, means for holding said plate against rotation, an adapter connected to rotate with the spindle and having a screw-threaded connection with said screw shaft, a spring connected to the spindle and providing means for rotating the spindle and thereby moving the pusher plate downward and causing it to push the said cap downward and tighten it on the jar, and speed control means for limiting and determining the speed at which the pusher plate is moved downward by the spring.

4. A machine for tightening caps on jars comprising a support for a jar with a cap loosely seated thereon, a vertical cap tightening spindle spaced above said support, a pusher plate beneath said spindle, a screw shaft fixed to said plate in

vertical alignment with the spindle, means for holding said plate against rotation, an adapter connected to rotate with the spindle and having a screw-threaded connection with said screw shaft, a face plate beneath and connected to the pusher plate, a resilient pad interposed between said plates, a coil spring surrounding and connected to the spindle and providing means for rotating the spindle and thereby moving the pusher plate downward and causing it to push the said cap downward and tighten it on the jar, and automatic means for rewinding the coil spring.

5. A cap tightening machine comprising a rotatable carriage, a support on the carriage for a container and cap, a pusher plate mounted above said support for movement up and down relative thereto, means for pushing said plate downward and thereby forcing the cap downward and tightening it on the container, said pushing means including a spindle, a spring, means for holding the spring under tension, means cooperating with the spring for causing the tension thereof to rotate said spindle, a stationary cam and means on the carriage controlled by said cam for determining and controlling the time and speed of rotation of the spindle by the spring, and means interposed between said spindle and pusher plate providing driving connections by which the rotation of the spindle applies a straight downward movement to said plate.

6. A machine for sealing caps to containers comprising a rotatable carriage, a support on the carriage for a container, a pusher plate positioned above said support, a cap tightening spindle mounted on the carriage above and in vertical alignment with said support and pusher plate, an arm mounted on the carriage for swinging movement, a coil spring held under tension, means interconnecting the spring with said arm and spindle for causing the spring to swing said arm and rotate the spindle, means providing a

driving connection between the spindle and said pusher plate by which rotation of the spindle imparts vertical movement to said plate, means for holding the latter against rotation with the spindle, a stationary cam, a cam follower roll carried by said arm and running on the cam and thereby retarding and controlling the movement of said arm and said rotation of said spindle.

7. The combination of a carriage rotatable about a vertical axis, a support for a container, said support being mounted to rotate with the carriage, a pusher plate positioned over and spaced above said support, a vertical spindle mounted on the carriage, a screw shaft fixed to said pusher plate in alignment with the spindle, an adapter attached to the spindle and having a screw-threaded connection with said shaft whereby rotation of the spindle imparts vertical movement to the pusher plate, means for holding the pusher plate and screw shaft against rotation with the spindle, a coil spring held under tension and operatively connected to the spindle for rotating the latter and thereby causing the pusher plate to push a cap down into tightened position on the said container, a stationary cam, and means operated thereby for rewinding the spring.
